UNITED STATES PATENT OFFICE

CARL LITTLEFIELD, OF BATTLE CREEK, MICHIGAN, ASSIGNOR TO BATTLE CREEK
BREAD WRAPPING MACHINE COMPANY, OF BATTLE CREEK, MICHIGAN

CONVEYER MECHANISM

Application filed March 12, 1932. Serial No. 598,492.

The main objects of this invention are:

First, to provide automatic means for mechanically transferring articles such as sliced loaves from a delivering means such as a slicing machine to receiving means such as a wrapping machine.

Second, to provide feed mechanism for transferring sliced loaves individually from one machine to another with a rolling action of the transfer members in the direction of movement thereof and a slightly compressive action for closing the spaces between the slices.

Third, to provide means whereby the feeding mechanism is only actuated when an article to be transferred is delivered thereto.

Fourth, to provide a mechanism of this type that is simple in construction, economical to manufacture, and effective and positive in operation.

Fifth, to provide means for translating articles such as sliced loaves without displacing the slices or injuring or crushing the loaves.

Objects relating to details and economies of my invention will appear from the description to follow. The invention is defined and pointed out in the claims.

A structure which is a practical embodiment of my invention is illustrated in the accompanying drawings, in which:

Fig. 1 is a fragmentary view in side elevation of feed mechanism embodying the invention.

Fig. 2 is a fragmentary top plan view of the apparatus partially broken away and showing parts in horizontal section.

Fig. 3 is an enlarged fragmentary perspective view of the mechanism.

Fig. 4 is a diagrammatic representation illustrating the operation of the feed mechanism.

In the accompanying drawings I have illustrated my improvements embodied or adapted for use in connection with a slicing machine for slicing loaves of bread and a wrapping machine for wrapping the sliced loaves. Only such portions of these machines are illustrated as are deemed neces-

sary to illustrate a practical embodiment of my improvements.

1 represents a slicing machine and 2 a wrapping machine. One of the sliced loaves is shown at 3. The sliced loaves are delivered from the slicing machine over a delivery table 4 to a feed table 5 disposed at the receiving end of the wrapping machine, this table supporting the articles to be wrapped in position to be engaged by grippers 7 which transfer the articles to be wrapped from the table to the conveyer way 11 along which the articles are propelled by the flights 9 carried by the endless conveyer chains 10. The grippers position the articles on the conveyer way so that they are picked up and moved along on the way by the flights and between the side rails or guides 111.

The grippers are preferably of oval shape and are mounted for a combined planetary and rotative movement so that they grip the ends of the articles to be translated, much as a pair of hands, and carry them along without materially varying or increasing the gripping pressure and at the same time maintaining such pressure that articles such as sliced loaves may be effectively handled.

The driving means for the grippers is controlled by the articles 3 which, as they are fed on to the table, engage the tripping trigger 17. This driving means in the mechanism illustrated comprises a shaft 12 provided at its outer end with a slip friction drive 13. The slip friction drive is in turn connected to and driven by the continuously driven chain belt 14, the power means not being illustrated.

The slip friction drive 13 is provided with an engaging pawl 15 which is controlled by the tappet 16 mounted on a rock-shaft 23 and normally lying in the path of the slip friction drive pawl so that the slip friction drive is disengaged at the end of each cycle of movement unless there should be a continuous feeding of articles to be wrapped under the feed table. In other words, the feeding of the articles on to the feed table controls the clutch.

This control means consists of trips 17 projecting through the feed table in posi-

55

100

tion to be engaged by the articles moved forwardly thereon. The trips are carried by the rockshaft 18 having the eccentrically disposed cranks 19 thereon engaging the lever 20 which is connected by the link 21 to the arm 22 on the rockshaft 23 so that actuation of the trip withdraws the tappet from pawl engaging position and engages the slip friction drive or allows it to engage.

10 The grippers are carried by arms 26 mounted on the vertical spindles 24 above the stationary gears 25. These arms are connected to and driven by the drive shaft 12 through the beveled gears 27 and 28. The grippers are journaled on the outer ends of the arms 26 and are provided with pinions 29 meshing with the stationary gears so that when the arms are rotated the grippers are 15 not only swung in their orbit but are rotated on their own axes. The grippers are preferably of oval shape and provided with facings 30 of soft resilient material such as sponge rubber.

20 25 The initial position of the grippers is such that when the trips 17 are engaged by the article to be wrapped the ends of the article are engaged by the grippers with a rolling action in the direction of movement thereof and in the direction of movement of the articles, so that the latter are gripped with a suitable pressure. Owing to the shape of the grippers this pressure is substantially constant during the translating movement of 30 the article and, while the articles are effectively gripped, delicate articles such as loaves of bread are not injuriously compressed, and sliced loaves of bread may be handled without likelihood of the slices being displaced. After the loaves have been 35 wrapped by the wrapping machine 2 they are discharged by the conveyer indicated generally by the numeral 31.

40 45 The oval shape of the grippers 7 is best illustrated by Figs. 2 and 4. These figures also clearly illustrate the simultaneous rolling and gripping actions of the grippers. The latter are adapted to be moved through a complete cycle of operation every time the trigger 17 is actuated. When the cycle is completed, if another loaf is not presented so as to actuate the trigger 17 again, the tappet 16 in the path of the pawl 15 operates to open the slip friction drive 13 to 50 disconnect the driving means from the drive shaft 12.

55 60 The oval grippers 7 are pivoted off center so that the sliced loaves 3 are initially engaged by the surface of the grippers at a short radius from their centers. As the grippers are rotated about their fixed axes and also about their revolving axes in the direction of the article being transferred or fed, the surface of the grippers rolls over 65 the ends of the loaf until the latter has been

70 transferred to the way member 11. The shape of the oval members 7 is such that the ends of the loaf are gripped positively throughout the entire gripping cycle without undue or excessive pressure on the loaf. For this purpose the grippers are covered 75 with the soft rubber facings 30 which absorb any slight variations in pressure on the loaf by the grippers.

80 85 By virtue of the gear ratio between the pinions 29 and the stationary gears 25, the operation of the feed mechanism is relatively quick compared to the operation of the drive shaft 12. This is desirable for the reason that the sliced loaves are moved out of the way of succeeding loaves being discharged by the slicing machine 1, and also for the reason that the sliced loaves must be placed relatively quickly between the flights 9 of the conveyer 10 of the wrapping machine to prevent damage to the loaves.

90 95 I have illustrated and described my improvements in a practical embodiment and, as stated, in association with a slicing machine and bread wrapping machine. I have not attempted to illustrate or describe various other adaptations or uses of which my invention is capable as it is believed that this disclosure will enable those skilled in the art to embody or adapt my improvements as may be desired.

100 Having thus described my invention what I claim as new and desire to secure by Letters Patent is:

1. In an apparatus of the class described, 100 the combination with a conveyer way, of an endless conveyer provided with flights operatively associated with said way for propelling articles along the way, a feed table disposed at the front end of said conveyer way, a delivery table disposed to deliver to said feed table and provided with guide members for supporting and guiding the articles as they are delivered to said feed table, transfer means operatively associated with said feed table and comprising oval rotary grippers having resilient facings, rotatably mounted arms on which said gripper members are rotatively mounted disposed so that the grippers engage the ends of the articles on said feed table and deliver the same to said conveyer way, stationary gears, said grippers having pinions meshing with said gears whereby said grippers are simultaneously given a planetary and rotating movement upon the actuation of said arms, driving means for said arms including a rotatable slip friction drive member, a tappet for releasing said slip friction drive member at a predetermined point in its rotation, and trip means for said tappet controlled by the articles delivered to said table.

110 115 120 125 130 2. In an apparatus of the class described, the combination with a conveyer way, of an endless conveyer provided with flights oper-

- atively associated with said way for propelling articles along the way, a feed table disposed at the front end of said conveyer way, a delivery table disposed to deliver to said feed table and provided with guide members for supporting and guiding the articles as they are delivered to said feed table, transfer means operatively associated with said feed table and comprising oval rotary grippers having resilient facings, rotatably mounted arms on which said gripper members are rotatively mounted disposed so that the grippers engage the ends of the articles on said feed table and deliver the same to said conveyer way, stationary gears, said grippers having pinions meshing with said gears whereby said grippers are simultaneously given a planetary and rotating movement upon the actuation of said arms, driving means for said arms including a slip friction drive, and control means for said slip friction drive actuated by the articles delivered to said table.
3. In an apparatus of the class described, the combination with a conveyer way, of an endless conveyer provided with flights operatively associated with said way for propelling articles along the way, a feed table disposed at the front end of said conveyer way, a delivery table disposed to deliver to said feed table and provided with guide members for supporting and guiding the articles as they are delivered to said feed table, transfer means operatively associated with said feed table and comprising oval rotary grippers having resilient facings, rotatably mounted arms on which said gripper members are rotatively mounted disposed so that the grippers engage the ends of the articles on said feed table and deliver the same to said conveyer way, and stationary gears, said grippers having pinions meshing with said gears whereby said grippers are simultaneously given a planetary and rotating movement upon the actuation of said arms.
4. In an apparatus of the class described, the combination with a conveyer way, of an endless conveyer provided with flights operatively associated with said way for propelling articles along the way, a feed table disposed at the front end of said conveyer way, a delivery means disposed to deliver to said feed table and provided with guide members for supporting and guiding the articles as they are delivered to said feed table, transfer means operatively associated with said feed table and comprising rotary grippers, arms on which said gripper members are rotatively mounted disposed so that the grippers engage the ends of the articles on said feed table and deliver the same to said conveyer way, means for swinging said arms and simultaneously rotating said grippers including a slip friction drive member, a tappet for releasing said clutch at a predetermined point in its rotation, and trip means for said tappet controlled by the articles delivered to said table.
5. In an apparatus of the class described, the combination with a conveyer way, of an endless conveyer provided with flights operatively associated with said way for propelling articles along the way, a feed table disposed at the front end of said conveyer way, a delivery means disposed to deliver to said feed table and provided with guide members for supporting and guiding the articles as they are delivered to said feed table, transfer means operatively associated with said feed table and comprising rotary grippers, arms on which said grippers are rotatively mounted disposed so that the grippers engage the ends of the articles on said feed table and deliver the same to said conveyer way, means for swinging said arms and simultaneously rotating said grippers including a slip friction drive member, a tappet for releasing said clutch at a predetermined point in its rotation, and trip means for said tappet controlled by the articles delivered to said table.
6. In an apparatus of the class described, the combination with a conveyer way, of an endless conveyer provided with flights operatively associated with said way for propelling articles along the way, a feed table disposed at the front end of said conveyer way, a delivery means disposed to deliver to said feed table and provided with guide members for supporting and guiding the articles as they are delivered to said feed table, transfer means operatively associated with said feed table and comprising rotary grippers of oval section, arms on which said grippers are rotatively mounted disposed so that the grippers engage the ends of the articles on said feed table and deliver the same to said conveyer way, and means for swinging said arms on fixed axes and simultaneously rotating said individual grippers.
7. In an apparatus of the class described, the combination with a conveyer way, of an endless conveyer provided with flights operatively associated with said way for propelling articles along the way, a feed table disposed at the front end of said conveyer way, a delivery means disposed to deliver to said feed table and provided with guide members for supporting and guiding the articles as they are delivered to said feed table, transfer means operatively associated with said feed table and comprising grippers mounted for simultaneous planetary and rotating movement, driving means for said grippers including a rotatable slip friction drive member, a tappet for releasing said clutch at a predetermined point in its rotation, and trip means for said tappet controlled by the articles delivered to said table.
8. In an apparatus of the class described, the combination with a conveyer way, of an endless conveyer provided with flights operatively associated with said way for prop-

10 pelling articles along the way, a feed table disposed at the front end of said conveyer way, a delivery means disposed to deliver to said feed table and provided with guide members for supporting and guiding the articles as they are delivered to said feed table, and transfer means operatively associated with said feed table and comprising grippers of oval section mounted and driven for simultaneous planetary and rotating movement about fixed and rotating axes.

15 9. In an apparatus of the class described, the combination with a conveyer way, of an endless conveyer provided with flights operatively associated with said way for propelling articles along the way, a feed table disposed at the front end of said conveyer way, a delivery means disposed to deliver to said feed table and provided with guide members for supporting and guiding the articles as they are delivered to said table, transfer means operatively associated with said feed table and comprising rotary oval 20 grippers having soft resilient facings mounted and driven for simultaneous planetary and rotating movement.

25 10. In an apparatus of the class described, the combination of a feed table, transfer means operatively associated with said feed table and comprising rotary grippers, rotatively mounted arms on which said gripper members are rotatively mounted disposed so that the grippers engage the ends of the articles on said feed table and deliver the same to said conveyer, stationary gears, said grippers having pinions meshing with said gears whereby said grippers are simultaneously given a planetary and rotating movement upon the actuation of the said arms, 30 driving means for said arms including a rotatable slip friction drive member, a tappet for releasing said slip friction drive member at a predetermined point in its rotation, and trip means for said tappet controlled by the articles delivered to said table.

45 11. In an apparatus of the class described, the combination of a feed table, transfer means operatively associated with said feed table and comprising rotary grippers, rotatively mounted arms on which said gripper members are rotatively mounted disposed so that the grippers engage the ends of the articles on said feed table and deliver the same to said conveyer, stationary gears, said grippers having pinions meshing with said gears whereby said grippers are simultaneously given a planetary and rotating movement upon the actuation of said arms.

50 12. In an apparatus of the class described, the combination of a feed table, transfer means operatively associated with said feed table and comprising grippers mounted for simultaneous planetary and rotating movement, driving means for said grippers including a slip friction drive, means for re-

leasing said slip friction drive at the end of each cycle, and control means for said releasing means controlled by the articles delivered to said table.

55 13. In an apparatus of the class described, the combination of a feed table, transfer means operatively associated with said feed table and comprising grippers of oval section mounted for simultaneous planetary and rotating movement. 75

14. In an apparatus of the class described, the combination of a feed table, transfer means operatively associated with said feed table and comprising oval grippers having soft resilient facings mounted for simultaneous planetary and rotating movement. 80

15. In a bread wrapping machine, the combination with means for delivering sliced loaves and means for receiving said sliced loaves, of means for transferring said sliced loaves from said delivery to said receiving means comprising spaced rotary grippers faced with soft resilient material adapted to engage the ends of said sliced loaves and move said loaves between them, and means for rotating said members simultaneously about fixed centers and about their own centers whereby said sliced loaves are transferred by the rolling action of said members, which tends to compress the slices of said loaves together in the transferring operation. 85

16. In a bread wrapping machine, the combination with means for delivering sliced loaves and means for receiving said sliced loaves, of means for transferring said sliced loaves from said delivery to said receiving means comprising spaced gripping members adapted to engage the ends of said sliced loaves and move said loaves between them, and means for rotating said members simultaneously about fixed centers and about their own centers whereby said sliced loaves are transferred by the rolling action of said members, which tends to compress the slices of said loaves together in the transferring operation. 90 105

17. In a bread wrapping machine, the combination with means for delivering sliced loaves and means for receiving said sliced loaves, of means for transferring said sliced loaves from said delivery to said receiving means comprising spaced rotary gripping members of oval section faced with soft resilient material adapted to engage the ends of said sliced loaves and move said loaves between them, and means for rotating said members whereby said sliced loaves are transferred by the rolling action of said members which tends to compress the slices of said loaves together in the transferring operation. 115 120

18. In a device of the class described, the combination with a pair of spaced rotary gripping members adapted to rotate about fixed parallel axes and simultaneously about their own rotating axes, and means for oper- 125 130

ating said members through one complete cycle of operation each time an article is presented therebetween.

19. In a device of the class described, the combination with spaced rotary gripping members adapted to rotate about fixed axes and simultaneously about their own rotating axes, and means for operating said members each time an article is presented therebetween.

In witness whereof I have hereunto set my hand.

CARL LITTLEFIELD.
